UNITED STATES PATENT OFFICE.

JAY G. SWAB, OF BROOKLYN, NEW YORK, ASSIGNOR TO HENRY TRENCHARD, JR., OF BROOKLYN, NEW YORK.

BLANK-FEEDING DEVICE.

Application filed May 16, 1923. Serial No. 639,278.

The present invention relates to mechanism for feeding paper sheets or blanks one by one from a supply stack to a machine.

The invention has been developed to pro-

5 vide means for feeding envelope blanks to an envelope forming machine and such an embodiment will be described for the purpose of illustration but such description is illustrative merely and is not intended as defining the limits of the invention.

10 It is important in machines for forming articles such as envelopes from previously cut paper blanks that the blanks be fed one at a time and accurately in predetermined 15 position in order that the folds may register exactly with the several parts of the blank.

15 The invention has for an object to provide improved means for reliably releasing 20 blanks from a supply stack one by one and feeding them accurately in predetermined position to a machine operating thereupon.

25 A further object is to provide means operative during the passage of the blank through the machine for insuring accurate 30 registration of the blank with respect to the lines of fold.

35 The nature of the invention and other objects thereof will be better understood from a description of a selected illustrative embodiment thereof. A mechanism for feeding envelope blanks to an envelope forming machine has been selected for particular description and is shown in the accompanying drawings forming a part hereof, wherein—

40 Figure 1 is a side elevation of a feeding mechanism forming a part of an envelope making machine constructed in accordance with the invention.

45 Figure 2 is a front elevation of the same.

Figure 3 is a view in side elevation taken from the opposite side of the machine.

50 Figure 4 is an enlarged section view taken on the line 4—4 Figure 2.

55 Figure 5 is a view substantially in elevation indicating the manner of registering the blank in the grippers.

Figure 6 is a detail view of the gripper operating cam.

60 Figure 7 is a detail view of the separator roll.

Figure 8 is a detail view of the suction picker.

65 Figure 9 is a detail sectional view taken

on the line 9—9 Figure 2 showing the feed roll control cam mechanism.

Figure 10 is a detail sectional view of the gripper roll mechanism.

70 Figure 11 is a view showing the gripper roll adjusting means.

75 In the mechanism shown, a supply of envelope blanks is provided in a stack 5 supported in inclined position and the blanks are fed one by one from the bottom of the stack being first engaged at their upper edges. This arrangement of the stack is preferred but is not essential.

80 In operation the upper edge of the bottom blank is released from its support upon a hollow perforated separator member 6 by inward rotation of said member to buckle the blank near its edge and release it from support by said member. Simultaneously or thereafter a suction picker 7 engages said blank toward its edge and swings the upper end thereof downwardly to the position indicated at 8 in Figure 4 where it is engaged by a pair of feed rolls 10, 11 and thereby carried forward and upward to a conveyor gripper roll 12 on the shaft 13 which will be 85 considered the drive shaft of the feeding mechanism. This gripper roll engages the blank at spaced points and carries it forward between said gripper roll and a cooperating presser roll 15 as indicated in Figures 1 and 4.

90 The hollow perforated suction member and support 6 as shown is in the form of a rotatable hollow shaft of relatively small diameter having perforations 16 along its blank engaging portion. Means is provided for rotating this shaft through an arc which is slightly greater than the distance from the point of support of said hollow shaft to the adjacent edge of the engaged 95 blank. The operation of this member is such that suction may be maintained therein at all times during the operation of the machine. It is unnecessary, however, to maintain the suction except during the time of rotation of said roll clockwise as shown in Figure 4, to release a blank and counter-clockwise to restore the roll to its normal position. The maintenance of suction during the return movement is preferred in order that the member may tend more effectively to restore to flat condition any engaged blanks which may have been slightly buckled 100 105

or disturbed during the operation of freeing the preceding blank.

The buckling of the bottom sheet downwardly by the rotation of the separator roll 6 is facilitated by a slight initial curvature of the sheets as best shown in Figure 4. As there shown, it will be noted that the supporting roll 6 is slightly above the plane of the top of the stack support thus causing a slight curvature of the sheets adjacent said roll and between it and the upper edge of the stack support. The difference in level between the top of stack support and the top of the separator roll 6 is somewhat exaggerated in other figures. This arrangement is preferred for the reason that if the sheets are entirely straight, the stiffness of the sheet might be sufficient to cause a slipping between the rotating separator roll 6 and the bottom sheet thus preventing release of the sheet and causing unreliable operation of the machine. The curvature, however, is preferably not too much because if the roll 6 is too high the stiffness of the paper may be such as to cause an excessive weight upon said roll thus possibly interfering with the perfect operation of the separator roll.

The suction picker 7 engages the bottom blank and draws the same downwardly to position to be engaged by the feed rolls 10, 11 as shown most clearly in Figure 4. The rotatable separator member 6 and the suction picker 7 are timed preferably to operate substantially in unison so that the action of each assists the operation of the other. The suction in the suction picker is preferably maintained only during its operative period, that is to say, from the time the picker engages the blank until the feed rolls 10, 11 engage the same. When the operative movements of the separator roll 6 and the picker 7 are suitably timed both may be connected to one suction tube and one valve may control the suction in both.

The suction of the separator 6 upon the freed blank is automatically broken by the rotation of said member in that as it rotates past a certain point the blank is no longer in engagement with the roll or supporting member at the point where the same is perforated. The exhaust passages connected with the separator are however relatively small so that the suction of the picker is not thereby released.

In the construction shown, the separator 6 and picker 7 are connected to a source of suction by means of a flexible tube 17. A valve 18, actuated by a cam 19 on the drive shaft controls the suction.

The mechanism shown for rotating the hollow supporting member comprises a lever 20 connected to an arm on said supporting member 6 by means of a suitable link 22 and actuated by means of a cam 23 on the drive shaft 13 through a link 25 as shown in Fig-

ure 4. The suction picker shown comprises several suction arms of different lengths to correspond generally to the contour of the forward edge of the blank. The three central arms 7^a engage the blank at the position 70 of the forwardly projecting flap. The side arms 7^b and 7^c are shorter and may engage the blank where the flap projects or at the side wings depending upon the width and style of envelope blanks being fed. The 75 three central arms 7^a are of such length that the lower feed roll 10 is recessed to receive the ends thereof as is indicated in Figures 4 and 8. The other arms are shorter and do not interfere with the roll. The picker arm 80 7 may be operated by any suitable mechanism. As shown in Figure 1 a pinion 27 is provided on the end of the picker shaft which pinion is actuated by a rack 28 controlled by a positively acting double cam 30 85 on the main drive shaft. The rack member 28 is provided with rollers 31, 32 projecting from its opposite faces and engaging the two parts of the double cam 30 to give the suction picker 7 a downward movement and return. While the free edge of the separated blank is held in lowermost position by the feed rolls to be drawn from the bottom of the stack thereby. 90

In the operative position shown in Figures 1 and 4 the upper feed roll 11 is in a position to interfere with the downward movement of the picker 7 and of the separated blank carried thereby. Means is provided, however, for moving the upper roll out of such position to permit free downward movement of the blank and picker arm and to return the roll to operative position after the blank has been carried down to roll engaging position. In the arrangement shown the upper roll is mounted in a frame 35 comprising two substantially similar side members, one on each side of the machine. These side members are connected at their upper ends by a tubular member 38 open at its lower side for the greater portion of its length, as indicated at 39 in Figure 4 and at their lower ends by tubular rod 40. The upper feed roll 11 is rotatably mounted in 100 the slotted tubular member in bushings 46, this construction being preferred for the reason that a greater rigidity of the frame can be obtained. 110

The frame 35 is oscillated about the lower 120 roll shaft by means of a link 41, pivotally connected to the frame as indicated in Figure 3 and controlled by a positively acting double cam mounted on the main drive shaft as indicated in Figures 2 and 3. Both of 125 the feed rolls 10 and 11 are positively driven from a gear 42 on the drive shaft 13 through an idle pinion 43, a gear 44 fixed to the lower feed roll shaft and a pinion 45 secured to the upper feed roll shaft. 130

If the feed rolls 10, 11 are in constant engagement with each other, any inaccuracy in the position of the forward edge of the blank when it is first engaged by the feed 5 rolls as they move to operative position will cause the blank to be pulled first toward one side with a resulting tendency for the inaccuracy of the position of the blank to be increased during its movement between 10 the feed rolls. In order to avoid any inaccuracy in the feeding movement from this cause, the two rolls are separated and the blank inserted therebetween, after which the rolls are brought together to engage the 15 blank and feed it forward.

The separation of the feed rolls 10, 11 in the illustrated arrangement to receive the blank therebetween is accomplished by an arrangement wherein the upper roll 11 is 20 raised when it is swung to the left and is again lowered when it is returned to its operative position shown in full lines in Figure 4. In the structure illustrated the rocking frame is permitted a slight substantially vertical movement relative to the lower feed roll shaft on which it is pivoted. This is accomplished by making the bore which engages said shaft in the form of a slot as indicated at 47 in Figure 4. That 25 portion of the tubular member 38 at the upper end of said frame which lies beyond the end of the slot 39 at each end is arranged to ride upon a cam plate 48 secured to the supporting frame as best shown in Figure 9. These cams are so shaped that upon rearward movement from the operative position 30 the tubular member 38 rides up upon the cams, one at each side of the machine, thus lifting the upper roll 11 away from the lower cooperating feed roll. In order to insure proper engagement of the rolls when the frame 35 is swung to its operative position, the frame and therefore the upper roll is pressed downwardly at each side of 35 the machine by a spring pressed plunger 50 mounted in a bracket 51 and acting on a pivoted arm 52. The rocking of the frame thus causes the engagement and separation of the feed rolls as well as the movement 40 of the upper roll 11 to and from operative position.

The blank after it passes between the feed rolls 10, 11 is engaged by a yieldable skid 55 which deflects it upwardly whence it 55 passes between this guide and a cooperating guide 56 to the gripping conveyor roll 12. As shown the gripping conveyor roll is made in adjustable sections. As shown in Figure 5 it consists of two spaced gripping 60 sections 56, 57 which are preferably supplemented by additional bearing rolls 58, 59 at either side adapted to engage the side wings of the envelope blank. The gripper sections each comprise a pair of mating drums 60, 65 61, the gripper being mounted in the drum

60. The opening and closing movement of the gripper is cam controlled as will be best understood from Figures 4, 5, 6 and 10. The radial movement of the gripper is controlled by means of rollers 62, 63 secured to 70 the radially movable gripper member 64 and engaging cam slots 65, 66 in the drum 60. The direction of movement, so controlled, is such that when the gripper is in open 75 position it is retracted peripherally a distance substantially equal to the length of the gripper jaw 69. This diagonal movement of the gripper jaw accomplishes two functions. The jaw is retracted peripherally when open to permit engagement of the 80 blank will the roll and removal therefrom without interference with the jaw and the forward closing movement aids in adjusting the forward edge of the blank to exact registering position. The gripper jaw 69 is 85 pivotally mounted on the outer end of the gripper member 64 and a spring 70 engaging the rear end of the jaw member urges the jaw resiliently into blank gripping position. 90

The opening and closing movement of the gripper member 64 is cam controlled. It is provided with a projecting boss 73 which extends through a slot 74 and carries at its outer end a roller 75 cooperating with a cam 76. This cam is loosely mounted on the shaft 13 and is held against rotation by means of an arm 77 thereon secured to a suitable part of the machine frame. This method of controlling the gripping movement of the grippers gives thereto a relatively slow motion as compared with the free, rapid snapping motion which is afforded when the jaws are closed by spring pressure with a snapping action. As above described the radial movement of the grippers is such that when the gripper jaws are in open position they are relatively retracted and when in closed position they are moved inwardly and forwardly to engage the paper. As shown in Figure 4, the paper moves upwardly between the guides 55, 56 into position for engagement by the grippers. In order to insure accurate positioning of the paper blank, the two grippers 69, 69 are positioned to engage the blank in the corners *a*, *b*, between the flap and wing portions. The blank is fed forward to the gripper rolls at a speed which is slightly in excess of that of the peripheral speed of these rolls so as to force the paper snugly into position against the grippers to be accurately registered thereby. The peripheral speed of the feed rolls may be for example about 10% in excess of the peripheral speed of the gripper rolls to accomplish this function. By this arrangement as shown in Figure 5, as the paper is moved forward relative to the grippers, the edges of the forward flap of the blank engage against the 125 130

grippers and the paper will thus be guided into the desired registering position.

The blank is further adjusted by the closing movement of the grippers which as they move forward to closed position engage first the tapered side edges *c*, *d*, and finally the corners *a*, *b*. The blank readily buckles to permit the forward edge portion to be moved to exact registered position and the movement of the grippers under cam control is slow enough to permit it to assume the correctly adjusted position with the corners *a*, *b*, snugly against the similarly formed inner faces of the gripper jaws before the jaws reach clamping position against the gripping rolls. The slow movement avoids the tearing of the edges of the blank.

In setting up the machine the gripping rolls may be adjusted peripherally to operate in suitable timed relation to the other parts of the machine by rotating the roll and shaft as a whole while the driving gear is loose on the shaft. It is occasionally desirable, however, to make a fine adjustment of one gripping roll section relative to the other to correct a tendency of the envelope blank to twist slightly in the machine. Provision is made for such adjustment by means of a pin or screw 80 having an eccentric end 81 which engages a slot 82 in the shaft. The clamping screw 83 may be released and the roll adjusted by means of this eccentric device whereupon the clamping screw is again tightened. This arrangement also provides for lateral adjustment of the rolls to accommodate envelope blanks of different widths without loss of the peripheral adjustment. When such lateral adjustment is desired the clamping screw 83 is released and the gripping roll moved laterally to desired position, the eccentric pin 80 then serving by its engagement with the slot in the shaft to maintain the peripheral adjustment of the roll.

The operation of the apparatus will be apparent from the foregoing description. A supply of blanks is placed upon the stack support with the edges as nearly even as possible. The separator and supporting roll 6 is rocked clockwise, as shown in Figure 1, to release the bottom blank from support thereby and to buckle it downwardly adjacent said roll. The suction picker 7 is operated to function simultaneously with the separator roll 6, that is to say, the suction picker engages the sheet to draw it downwardly at about the same time that the separator roll 6 functions to release said sheet. Immediately upon the completion of the downward movement of the suction picker and the blank carried thereby, the rocker frame 35 swings to carry the feed roll 11 to its operative position as shown in full lines in Figure 1. The cams 48 cooper-

ating with the frame hold the frame in lifted position and the roll 11 out of contact with its companion roll 10 during the forward movement and until the roll 11 practically reaches its final operative position, whereupon the frame passes over the forward edges of the cams and drops into operative position engaging the blank along the line spaced slightly inwardly from the edge of the sheet and incidentally, it engages the sheet throughout the full engaged width simultaneously. As the frame 35 and roll 11 approach operative feeding position the tubular member 39 comes into engagement with the presser member 50 which insures downward movement of the frame and roll.

The feed rolls are constantly driven through the constantly meshing gears 44, 45 so that immediately upon engagement with the paper, the feeding operation begins. The feed rolls 10, 11 carry the blank forward and up between the guides 55, 56 into position to be engaged by the gripping rolls. At the time the forward end of the blank approaches the grippers 68 they are in open and peripherally retracted position under control of the cams 76. The blank first engages the periphery of the gripper roll 12 at a point which may be substantially in front of the jaw 69 but the peripheral speed of the feed rolls 10, 11 is substantially ten per cent in excess of that of the gripper rolls so that the blank is moved forwardly under the gripper jaws 69. About the time the forward edge of the blank reaches a suitable position the gripping jaws are actuated by the cams 76 to move them forwardly against the side edges *c*, *d*, of the forwardly projecting flap portion of the blank and into the corners *a*, *b*. As soon as the blank is clamped by the grippers, it is released from feeding engagement by the feed rolls 10 and 11. The frame 35 is again rocked, whereupon the roll 11 is immediately raised due to the fact that the cam engaging portion of the tubular member 39 rides up the sloping forward ends of the cams 48.

As the frame 35 and roll 11 moves rearwardly the tubular member 39 of the frame engages the guide 55 and moves it rearwardly against the action of the spring 55'.

The arrangement illustrated affords reliable means for feeding blanks accurately to predetermined position and is particularly valuable in the manufacture of special articles requiring accuracy of registration. While the particular description refers more particularly to its application to an envelope machine, such reference is merely by way of illustration and is not intended as defining the limits of the invention.

I claim:

1. In a paper feeding device of the character described in combination means for

supporting a stack of paper blanks, air suction means engaging the under side of the bottom blank near one edge and movable inwardly to buckle the blank downwardly and 5 means for engaging the buckled blank and withdrawing it from the stack.

2. In a blank feeding apparatus of the character described for feeding blanks from the bottom of a stack of blanks, in combination 10 a hollow perforated supporting member extending parallel to one edge of the blanks of the stack, means for rotating said member inwardly to release the bottom blank and means for creating suction therein during 15 the period of rotation.

3. In a blank feeding apparatus of the character described for feeding blanks from the bottom of a stack of blanks, in combination 20 a hollow perforated supporting member extending parallel to one edge of the blanks of the stack, means for rotating said member inwardly to release the bottom blank and means for creating suction therein during 25 the period of rotation, and means for gripping the released bottom blank and withdrawing it from the stack.

4. In a paper feeding device of the character described, in combination, means for supporting a stack of paper blanks, air suction means, movable inwardly from one edge 30 to release the edge portion from its support and a suction picker engageable with the released portion to further separate the bottom blank from the stack.

5. In a blank feeding apparatus of the character described for feeding blanks from the bottom of a stack of blanks, in combination 40 a hollow perforated supporting member, extending parallel to one edge of the blanks of the stack, means for rotating said member inwardly to release the bottom blank and means for creating suction therein during the period of rotation, a suction member engageable with the released edge 45 portion and operative to bend the same downwardly and gripping means engageable with said edge portion to draw the blank from the stack.

6. In a feeding device of the character described, in combination, means for supporting a stack of paper blanks in an inclined 50 position whereby the weight on the bottom blank is substantially less than the weight of the stack, a hollow perforated supporting 55 member extending parallel to the upper edge of the blanks where the pressure is least, means for rotating said member inwardly to release the engaged edge portion of the bottom blank, means engageable with the said edge portion for withdrawing the blank 60 from the stack.

7. In a feeding device of the character described, in combination, means for supporting a stack of paper blanks in an inclined 65 position whereby the weight on the bottom

blank is substantially less than the weight of the stack, a hollow perforated supporting member extending parallel to the upper edges of the blanks where the pressure is least, means for rotating said member inwardly to release the engaged edge portion 70

of the bottom blank, means for bending the released edge portion downwardly, feeding rollers for gripping said bent-down edge portion and drawing the blanks from the stack and means for moving one of said feed rollers to and from blank gripping position. 75

8. In a blank feeding apparatus of the character described for feeding blanks from the bottom of a stack, in combination, a hollow perforated supporting member extending along and parallel to one edge of the blanks of the stack, means for rotating said supporting member through an arc slightly greater than the distance of the member from the edge of the blanks to release the bottom blank and means for creating suction therein during the period of rotation. 80

9. In a feeding device of the character described, in combination, a pair of feed rolls, a frame comprising a transverse tubular member and side members connected to the opposite ends thereof, and pivotally mounted upon the axis of the first feed roll, the second feed roll being rotatably mounted in said tubular member and said tubular member being open at one side to permit engagement of the feed roll therein with the first feed roll. 90

10. In a blank feeding apparatus of the character described, an air suction separator engageable with a blank near one edge to separate said blank from a stack of blanks and a suction picker engageable with said blank at a point further from the edge thereof to further separate said blank from the stack, substantially as described. 105

11. In a feeding device of the character described, in combination, a shaft, a feed roll mounted thereon, a frame pivotally mounted concentric with said shaft, a second feed roll mounted thereon, means for rocking the frame about its pivot to carry the second feed roll to and from operative 110 position and cam means for moving the frame to carry the second feed roll toward and from the first mentioned feed roll during the rocking movement of the frame. 115

12. In a feeding device of the character described, in combination, a shaft, a feed roll mounted thereon, a second feed roll and means to move it bodily toward the first mentioned roll and circumferentially with respect thereto. 120

13. In a feeding device of the character described, in combination, a pivoted frame, said frame comprising opposite side members and a tubular member connecting the same, said tubular member being open on 130

one side and a roll mounted in said tubular member and engageable through the slot of said tubular member substantially as and for the purpose described.

- 5 14. In a blank feeding apparatus of the character described for feeding blanks from the bottom of a stack, in combination, a hollow perforated supporting member extending along and parallel to one edge of
- 10 the blanks of the stack, means for rotating said supporting member through an arc slightly greater than the distance of the member from the edge of the blanks to release the bottom blank and back through the
- 15 same arc to replace displaced blanks and means for creating suction thereon during the period of rotation in both directions.
16. In a feeding device of the character described, in combination, a shaft, a feed roll mounted thereon, a frame pivotally mounted concentric with said shaft, a second

25 feed roll mounted on said frame, means for rocking the frame about its pivot to carry the second feed roll to and from operative position and means for moving the second feed roll toward and from the first mentioned feed roll during the rocking movement of the frame.

17. In a feeding device of the character described, in combination, a shaft, a feed 30 roll mounted thereon, a frame pivotally mounted concentric with said shaft, a second feed roll carried by said frame, means for actuating the frame to carry the second feed roll to and from operative position and 35 toward and from the first mentioned feed roll.

In testimony whereof, I have signed my name to this specification this 9th day of May, 1923.

JAY G. SWAB.
